SHOVEL

Filed Dec. 8, 1927

Inventor:
Frank D. Rugg.
by Harry, Booth, J. A. and Harry
Hays.

UNITED STATES PATENT OFFICE

FRANK D. RUGG, OF GREENFIELD, MASSACHUSETTS

SHOVEL

Application filed December 8, 1927. Serial No. 238,523.

This invention relates to a novel and improved shovel for handling snow and other materials. The invention will be best understood by reference to the following description, when taken in connection with the accompanying drawings of one specific embodiment thereof, while its scope will be more particularly pointed out in the appended claims.

10 In the drawings:

Fig. 1 is a perspective view of a shovel exemplifying the invention;

Fig. 2 is another perspective view of the shovel tipped up to show the bottom;

15 Fig. 3 is a plan on an enlarged scale of one corner of the blade, illustrating the construction of the sheath;

Fig. 4 is a vertical, longitudinal, sectional view of the shovel, on an enlarged scale; and

20 Fig. 5 is a detail, sectional view, on an enlarged scale, on line 5—5 of Fig. 4.

Referring to the drawings, and to the embodiment of the invention which is selected for exemplification, there is shown a shovel 25 having a blade comprising a bottom 10, two side walls 11, and a rear wall 12. In the present example, the bottom is a thin, sheet metal plate, which is light and yet sufficiently strong, especially owing to the way in

30 which it is related to the other parts, as will presently appear. The sheet metal plate also has an advantage over wood in this situation, because wood is apt to check and split. The sheet metal has the further advantage that

35 it keeps the shovel "in square" better than the usual wooden bottom. The side and rear walls, however, herein are of wood, which is well suited to the purpose. The bottom plate is conveniently secured to the side walls (see

40 Fig. 2) by fastening elements such as nails 13, driven through the plate and into the side walls.

In the present example, the plate extends beneath the rear wall, and thence upwardly along the rear face of the latter, in

45 which it is conveniently secured by fastening elements, such as nails 14. In cutting the plate, tabs 15 are left at the rear corners, and these extend rearwardly beyond the rear wall to the rear ends of the side walls to

50 which they are shown secured, thereby rein-

forcing the latter, and aiding in their resistance to wear.

Extending transversely of and beneath the bottom plate is a bar 16, conveniently made of wood, and preferably secured to the bottom plate and to the side walls, as by some of the fastening elements 13. This bar reinforces the bottom plate, herein adjacent its front end, and greatly adds to the rigidity

55 of the blade. The front edge of this bar is beveled as at 17, and it is provided with a

sheet metal sheath 18, to reinforce and protect the same, and to provide a cutting edge 19. The thickness of this sheath is greatly exaggerated in Fig 4, because of the small scale. The sheath is folded over the bar to present two walls 20 and 21, which embrace its upper and lower surfaces, and these walls are secured to the bar, as by fastening elements, herein rivets 22, which extend

60 through said walls and through said bar, as well as through a portion of the bottom plate

10, which is offset downwardly and extends beneath the wall 20. The lower surface of the reinforcing bar 16 in the present example is perfectly flat, and the lower wall 21 of the sheath is not set into the bar, as this is unnecessary, said wall being so thin that it presents no substantial obstruction at

65 its rear edge.

Herein, the lower wall 21 of the sheath is extended upwardly at each end (see Fig. 2), along the sides of the side walls 11, and thence inwardly and downwardly (see Fig. 3) to present a corner reinforcing tab 23, which is conveniently secured in place as by one of the rivets 22. In this way, the corner is greatly strengthened, and its resistance to wear and the effects of shocks is increased. It adds greatly to the durability

70 of the shovel.

The front ends of the side walls 11 slope rearwardly and upwardly; they are beveled as at 24, and provided with sheet metal sheaths 25, having inner and outer walls 26 and 27, which embrace the associated side wall, and are suitably secured thereto, as by nails 27. Herein, these sheaths, at their forward ends, are encompassed by the tabs

60

65

70

75

80

90

95

100

23 of the front sheath 18, so that one sheath reinforces the other adjacent the corner.

The rear wall, in the present embodiment, slopes upwardly and rearwardly, and is appropriately secured to the side walls by pro-

5 viding each of the latter with a groove 28, which receives the adjacent end of the rear wall, fastening elements 29 being driven through the side walls into the ends of the rear wall. Two runners 30, herein cylindri-

10 cal tubes, are disposed beneath the blade, and, as shown, extend thence rearwardly and upwardly along the outer face of the rear wall, and continue beyond the latter

15 rearwardly and upwardly to present handle bars 31, to which a handle 32 is conveniently attached by flattening the tubes, as at 33, to receive bolts 34 for the attachment of the handle. The forward ends of the runners

20 are suitably secured to the blade, as by flattening and offsetting the runners at 35, to receive bolts 36 extending through the runners, through the bar 16, and through the plate 10. The tubes are securely united with

25 the rear wall, as by bolts 37 extending through the tubes and through the rear wall. The bottom is supported and prevented from sagging by bars 38 (see Fig. 5), interposed between the runners and the bottom plate.

30 These bars are held against lateral displacement by being provided with grooves 39, which receive the tubes 30. Herein, the bars are rabbeted as at 40, to receive the rear edge of the transverse bar 16.

35 Inasmuch as the runners are made entirely of metal, I am enabled to avoid the use of the metal shoes usually employed on the bottoms of wooden runners. The all metal runner is much stronger and more durable

40 than the composite runner, especially as the metal shoes heretofore employed are apt to

break away from the wooden runners, particularly after they have become worn. Furthermore, by making the handle bars as integral extensions of the runners, the structure is much stronger than is the case with

45 separate handles bolted to the runners or to the bottom.

When the shovel is in use, the user grasps

50 the handle 32, and thrusts the shovel forward, tipping its front end downwardly to cause the cutting edge 19 to engage the surface which is being cleared of snow or other material.

When the shovel has gathered up

55 a sufficient load, the runners are allowed to rest flatwise on the ground or platform, and the shovel is pushed to a place where the load is to be deposited.

Having thus described one embodiment of

60 the invention, but without limiting myself thereto, what I claim and desire by Letters Patent to secure is:

1. In a shovel, the combination of a blade,

a rear wall, and a pair of runners, each com-

65 prising a continuous bar disposed in part

beneath said blade and extending thence rearwardly and upwardly behind said rear wall and continuing therebeyond rearwardly and upwardly, fastening means securing said bars to said blade and to said rear wall, portions of said bars rearwardly of thin front ends being spaced from the bottom of said blade, and blade supporting means interposed between said portions and the bottom of said blade.

70

2. In a shovel, the combination of a blade comprising a plate of sheet material, a bar extending transversely of and beneath said plate from its front end rearwardly, and a pair of runners disposed beneath said plate and secured to said bar.

75

3. In a shovel, the combination of a blade comprising a plate of sheet material, a bar extending transversely of and beneath said plate from its front end rearwardly, a pair of runners disposed beneath said plate and beneath said bar, and fastening means extending through said runners, through said bar and through said plate.

80

4. In a shovel, the combination of a blade comprising a plate of sheet material, a rear wall, and a pair of runners disposed in part beneath said plate and extending thence rearwardly and upwardly along the outer face of said rear wall, said plate extending upwardly along said wall.

85

5. In a shovel, the combination of a blade comprising a plate of sheet material, a rear wall, and a pair of runners disposed in part beneath said plate and extending thence rearwardly and upwardly along the outer face of said rear wall, said plate extending rearwardly beneath said wall and thence upwardly along the rear face of said wall, and fastening means securing the upwardly extending portion of said plate to said wall.

90

6. In a shovel, the combination of a bottom, side walls, and a continuous, one-piece sheath extending across the front of said bottom, and thence part way about and embracing each wall.

95

7. In a shovel, the combination of a bottom, side walls, and a sheath having upper and lower walls embracing the front edge of said bottom, one of said sheath walls being extended to form tabs which are wrapped part way about said side walls.

100

8. In a shovel, the combination of a bottom, side walls, and a sheath having upper and lower walls embracing the front edge of said bottom, one of said sheath walls being extended to form tabs which are wrapped part way about said side walls, the ends of said tabs being directed toward each other along said upper wall.

105

9. In a shovel, the combination of a bottom, side walls, and a sheath having upper and lower walls embracing the front edge of said bottom, said lower wall presenting tabs which extend upward on the outer faces

110

of said side walls, thence across said side walls, thence downward on the inner faces of said side walls and thence inward on the upper face of said upper wall.

5 10. In a shovel, the combination of a bottom, side walls, a sheath having upper and lower walls embracing the front edge of said bottom, one of said sheath walls being extended to form tabs which are wrapped part way about said side walls, and fastening elements which extend through said upper and lower walls, through said bottom and through said tabs.

10 15. In a shovel, the combination of a bottom, side walls having upwardly and rearwardly sloping front ends, sheaths having inner and outer walls embracing said sloping front ends of said side walls, and a sheath extending across the front of said bottom and extended to embrace the first-mentioned sheath.

20 25. In a shovel, the combination of a wooden side and rear walls, a sheet metal bottom plate extending beneath said walls and upwardly behind said rear wall, fastening elements extending through said plate into said side and rear walls, a pair of runners beneath said plate, and a handle rearwardly of said plate.

30 35. In a shovel, the combination of a sheet metal bottom plate, a wooden reinforcing bar beneath and secured to said plate, and a sheet metal sheath about the front edge of said bar.

35 In testimony whereof, I have signed my name to this specification.

CERTIFICATE OF CORRECTION.

Patent No. 1,766,691.

Granted June 24, 1930, to

FRANK D. RUGG.

It is hereby certified that error appears in the printed specification of the above numbered patent requiring correction as follows: Page 2, line 71, claim 1, for the word "thin" read "their"; and that the said Letters Patent should be read with this correction therein that the same may conform to the record of the case in the Patent Office.

Signed and sealed this 5th day of August, A. D. 1930.

(Seal)

**Wm. A. Kinnan,
Acting Commissioner of Patents.**
